UNITED STATES PATENT OFFICE.

CHARLES C. ZABRISKIE, OF DETROIT, MICHIGAN, ASSIGNOR TO THE SUPERIOR SEAL & STAMP COMPANY, OF DETROIT, MICHIGAN, A CORPORATION OF MICHIGAN.

EMBOSSING MACHINE.

Application filed November 6, 1922. Serial No. 599,325.

The invention relates to embossing machines and more particularly to that type designed for operation upon the walls of narrow necked containers, such, for instance, as milk cans. It is the object of the invention to provide a construction which is adapted to perform the embossing operation quickly and efficiently and which requires a minimum of time for engagement and disengagement. To this end the invention consists in the construction as hereinafter set forth.

In the drawings:

Figure 1 is a side elevation of the machine in position for engagement of the work;

Fig. 2 is a similar view of the embossing dies in position where the work is being performed;

Figs. 3 and 4 are end elevations of the dies respectively in the positions of Figs. 1 and 2.

In the embossing of the walls of sheet metal containers, such as milk cans, it is necessary to arrange the male and female dies respectively upon the outside and inside of the work and to apply the necessary pressure for the drawing of the metal. It is the usual practice to form these dies on the periphery of circular rolls, which in turn are mounted upon spindles or arbors revolvably supported in a frame. Where the container to be embossed has a comparatively narrow neck, as, for instance, a milk can, the circular die must be restricted in diameter so as to enter this neck. At the same time, it is essential that the periphery of the die should be brought into full contact with the inner wall of the can. Therefore, if the form of the die is cylindrical, it is only possible to form the work on articles in which the difference between the radius of the neck and of the body is no greater than the difference in the radius of the die and its spindle.

To adapt my machine for successful operation on articles having a greater difference between the size of the neck and body, I have substituted for the cylindrical dies conical dies, which are reversely arranged on the inner and outer spindles. These will permit of arranging the portion of the can to be embossed in oblique relation to the axes of the spindles and thereby to avoid interference between the neck portion of the can and the spindles. However, to engage the

can with the dies, a considerable clearance between the rolls is required for passing around the various bends between the neck and the body. If such clearance is obtained by movement of one of the spindles towards or from the other, this will introduce complexity in the construction and will also interfere with the rigidity of the structure during the performance of the work. I have avoided this difficulty by cutting away segments of the periphery of the dies, thereby providing the required clearance without any relative movement of the spindles. This produces an exceedingly simple and rigid construction which is capable of rapid operation with satisfactory results.

In detail, A is a frame upon which are mounted the parallel spindles B and C, these being journaled in suitable bearings D in the upwardly extending frame members E and F. G and G' are intermeshing gear wheels mounted on the respective spindles and which accurately time the rotation of said spindles in relation to each other. H is a driving mechanism for one of the spindles which is provided with any suitable construction of trip mechanism (not shown), effecting one complete revolution of each spindle each time the machine is operated.

The spindles B and C extend outward beyond the frame member E a considerable distance and the die members I and J are mounted at their outer ends. These dies are of frusto-conical form, being reversely arranged upon the spindles so as to be parallel to each other at the point of tangency. These tangent portions are also at an angle to the axes of the spindles such that the narrow neck of the can will clear the spindle of the inner die member.

Usually milk cans are formed with flaring mouths, a narrow cylindrical neck and an obliquely expanding portion extending from the neck to the cylindrical body. These changes in direction would cause interference in introducing or extracting the work if the clearance provided between the dies was merely that required for the introduction of straight work. Therefore, the usual adjustments which are provided in embossing machines for moving the dies towards or from each other would be insufficient to adapt this machine to the work which it is designed to perform. I have,

however, provided abundant clearance by cutting away segments of each die, as indicated at K and K', which cut-away portions are opposite each other in the normal 5 stationary position of the dies.

With the construction as described, the clearance between the portions K and K' will permit of quickly engaging the can or similar article so as to register the portion 10 of the wall to be embossed with the dies. The machine is then tripped, which will cause one complete revolution of each of the dies, first bringing the embossed portions in 15 contact with the outer and inner surfaces of the can and then rolling to complete the embossing operation. Finally the machine is stopped in its original position where the cut-away portions K and K' permit of disengagement of the completed work and the 20 re-engagement of a new blank.

What I claim as my invention is:

1. In an embossing machine, the combination of parallelly arranged rotary spindles, means for imparting to said spindles simultaneous and corresponding angular movements, and embossing dies co-actingly mounted on said spindles, having peripheral work engaging faces extending obliquely to the axes of rotation throughout substantially the full width of said faces, said faces being parallel along their lines of tangency to the work, said dies having cut-away portions of a radius less than that of any portion of said work engaging faces, 35 said portions opposing each other in one angular position of said spindles and being spaced apart in said position so as to afford a relatively large clearance for introduction and withdrawal of work.

2. In an embossing machine, the combination of parallelly spaced rotary spindles, journal bearings for said spindles affording rigid support therefor and arranged to leave outwardly projecting portions with an unobstructed space therebetween, complementary dies mounted on the outer ends of said spindles and provided with peripheral segments having surfaces which are oblique to the axes of rotation and parallel to each other along the line of tangency, said dies also having portions of their peripheries cut away, and means for periodically rotating said spindles simultaneously and correspondingly through predetermined angular movements thereby bringing the cut-away portions of said dies adjacent each other to permit introduction and withdrawal of the work.

3. In an embossing machine, the combination with parallelly arranged spacer rotary spindles, of a pair of complementary embossing dies mounted on said spindles, said dies having their peripheral work engaging faces inclined throughout substantially the entire width of said faces to a frustro-conical form, said faces being parallel along the lines of their tangency to the work, said dies having cut-away peripheral portions reduced to a lesser radius than any portion of said frustro-conical surfaces, said portions being opposed in one position of rotation of said spindles, and being spaced apart in said position to afford a relatively large clearance for the introduction and removal of work.

In testimony whereof I affix my signature.

CHARLES C. ZABRISKIE.
